UNITED STATES PATENT OFFICE.

CHACE D. GILMORE, OF BLOOMINGTON, ILLINOIS.

SALT AND PEPPER SHAKER.

1,237,632.

Specification of Letters Patent. Patented Aug. 21, 1917.

Application filed February 24, 1916. Serial No. 80,195.

To all whom it may concern:

Be it known that I, CHACE D. GILMORE, a citizen of the United States, residing at Bloomington, in the county of McLean and State of Illinois, have invented a new and useful Salt and Pepper Shaker, of which the following is a specification.

The present invention has reference to an improved salt and pepper shaker of the character wherein two or more condiments may be placed in one receptacle, in different sections thereof, and be distributed through a common perforated cap, the present invention having for an object to provide a device of this nature with improved means for establishing communication between one of the compartments of the shaker and the cap, and cutting off communication between the cap and the opposite compartment.

Another object of this invention is to provide a controlling valve, which alternately closes the compartments in the body of the shaker, and which at the same time is located, and so operated, that it serves as a scraper or cleaner to traverse the inner face of the cap and remove all accumulations of salt, or the like, which tend to clog up the apertures in the cap, and return the said accumulations to their respective compartments in the body. Thus, the improved valve not only serves to open the desired compartment in the body, but it also closes the other compartment, cleans the inner surface of the cap, returns the accumulations on the cap to the compartment from which the material was discharged, and provides an efficient means to prevent the accidental mixing of the condiments in the body. The improved valve is also adapted to be arranged to admit the discharge of the condiments from both compartments in the body at the same time, and may be adjusted to correctly proportion the discharge, as is found desirable.

A further important feature of the present invention is in the provision of a valve of this nature, which is operable from the outside of the receptacle, by a turning part, such as the cap, or a ferrule, or the like, which may be placed about the upper end of the body, so that it may be grasped from any side, and given a turn in either direction upon the body to throw the valve more or less to one side or the other, and thus secure the desired result. This feature of the invention embraces a novel means for stop-

ping the rotation of the rotatable part at the end of its turning movement in either direction, to thus provide means which indicate to the user that the valve is completely turned over in the desired direction, and also to indicate to the user, the relative position of the valve which is regulated by the relative turning of the rotatable part on the body.

A still further aim of the invention is to provide the body with improved means for opening and closing the bottom thereof, so as to admit of the deposit of the various condiments in the body, and to uncover or open but one compartment at a time, so that there is little danger of mixing the condiments in one compartment, or of depositing a condiment in the wrong compartment.

The present invention also aims at the provision of a device of this nature, which possesses all of the above advantages, and which at the same time is of the usual size and proportions of the ordinary condiment holder employed for containing and distributing one condiment, so that the invention does not contemplate the provision of a large or cumbersome device, which would preclude its general use, or which does not admit of attractive designs in its formation or construction.

The above and other objects and advantages of this invention will be more fully brought out in the following specific description of the present preferred embodiment of this invention, the same being illustrated in the accompanying drawings, wherein—

Figure 1 is a vertical central section, taken through a salt and pepper shaker, embodying the features of this invention, and showing the valve in position to close the compartment at the left side of the body.

Fig. 2 is a horizontal section, taken on the line 2—2 of Fig. 1, and looking down on the parts in the adjustment of Fig. 1.

Fig. 3 is a similar view, taken on the line 3—3 of Fig. 1, looking down on the parts, and showing the valve hinge and operating parts in section.

Fig. 4 is a horizontal sectional view, taken on the line 4—4 of Fig. 1, showing the arrangement of the fixed partition in the body, and the openings in the bottoms of the compartments thereof through which the condiments are poured in the filling of the body.

Fig. 5 is a horizontal sectional view, through the lower end of the body, taken on

the line 5—5 of Fig. 1, and showing a portion of the bottom broken away to disclose the filling opening in the closure disk in the base of the device.

5 Fig. 6 is a fragmentary vertical sectional view of the upper end of the device, showing the valve in a position opposite to that shown in Fig. 1, to close the compartment at the right side of the body, and open the 10 opposite compartment thereof.

Fig. 7 is a detail perspective view of the semispherical cap or dome employed, showing the flange of the cap and the depending stops therefor.

15 Fig. 8 is a fragmentary perspective view of the upper end of the body, showing the outstanding flange thereon with its stop shoulders, and showing the inturned lugs for holding the central partition in place.

20 Fig. 9 is a detail perspective view of the connecting ring adapted for engagement beneath the body flange.

Fig. 10 is a central sectional view, taken through the upper part of the device, at substantially right angles to Fig. 1, showing a slight modification of the valve operating means, and showing a side elevation of the valve in intermediate or raised position.

Fig. 11 is a horizontal sectional view, 30 taken on the line 11—11 of Fig. 10, and showing the valve and its operating parts in section.

Fig. 12 is a detail perspective view of the combined stop and connecting strap carried 35 by the valve.

Fig. 13 is a vertical sectional view, through the upper end of the shaker, showing a second modified form of the operating means.

Fig. 14 is a horizontal sectional view 40 through the same, on the line 14—14 of Fig. 13, showing the stops projecting from opposite sides of the valve, and showing the latter in vertical intermediate position.

Fig. 15 is a similar view, showing the 45 valve turned over in one direction, and showing a stop in engagement with one of the turning fingers to limit the movement thereof.

Fig. 16 is a side elevational view, partly 50 in section of the upper end of the shaker, embodying a third modification in the valve operating means.

Fig. 17 is a vertical sectional view of the device of Fig. 16, the section being taken at 55 right angles to the showing in Fig. 16, and through the hinge axis of the valve.

Fig. 18 is a vertical sectional view, taken 60 through the upper end of the shaker, embodying a fourth modification in the operating and supporting means for the valve, the view showing the cap and body in one piece, and wherein the ferrule and connecting ring only are rotated.

Fig. 19 is a vertical sectional view of the 65 same, taken on the line 19—19 of Fig. 18.

Referring to these drawings, wherein like parts are designated by similar numerals of reference throughout the several views, 20 designates the body of the improved shaker, which may be formed from sheet metal, cut 70

glass, or any other suitable and desirable material, for the purposes of manufacture and design. The body 20 is open at both ends and is preferably cylindrical, as shown in the drawings. As shown in Fig. 8, the body 75

20 is provided at its upper edge with a body flange 21 extending entirely thereabout, and projecting outwardly therefrom. The flange 21 has, in its opposite sides, relatively long peripheral recesses 22, terminating at their 80

opposite ends in stop shoulders 23. The flange 21, intermediate each pair of opposed stop shoulders 23, and at the recesses 22, is provided with lugs 24 struck from the flanges, and bent inwardly and downwardly 85

against the inner opposite walls of the body 20. These lugs 24 are suitably grooved as at 90

25 to receive therein the opposite edges of a diametrically extending partition 26 dividing the body 20 into two compartments, 27 95

and 28. The partition 26 extends from top to bottom in the body 20 and is provided upon its upper edge with spaced apart integral tongues 29, which are rolled over to provide cylindrical bearings adapted to receive therebetween, and in longitudinal alignment therewith, a plurality of interfitting 100

rolled tongues 30 integral with the inner diametrically extending edge of a substantially semi-circular valve 31. The interfitting tongues 29 and 30 are, as shown to advantage in Fig. 3, hingedly connected together by pins 32 and 33, the pins being introduced from the opposite lateral edges 105

of the partition 20 through the alining 110 tongues 29 and 30, so as to hingedly mount the disk valve 31 on the upper end of the partition 26.

Slid upwardly about the body 20 and engaging beneath the body flange 21 thereof, is 115 a connecting ring 34. This ring 34, as may be best seen from Figs. 6 and 9, comprises a band, which is preferably bent upon itself to provide a ring of double thickness, the combined thickness presenting a width at the 120 top of the ring equal to the width of the flange 21, so that the ring lies substantially beneath the body portion of the flange 21.

The ring 34, has its outer portion facing upwardly through the recesses 22 in the 125 opposite sides of the body flange and provided in its outer thickness and at diametrically opposed points with recesses 35, which are relatively narrow, but which open upwardly into the recesses 22 of the body flange.

Seated for rotation on top of the body 20 is a cap 36. This cap 36 is of dome shape, being substantially semi-spherical in contour, and having at its enlarged or base por- 130

tion an annular flange 37, seating upon the body flange 21, and being provided at diametrically opposed points with depending stops 38, projecting downwardly through the 5 recess 22 of the body flange, and adapted to snugly seat in the recesses 35 of the connecting ring 34. When the ring 34 is turned, the stops 38, being held in the recesses 35, are forced to turn with the ring and carry 10 the cap 36 therewith. The stops 38 are limited in their movement in either direction by the stop shoulders 23 at the ends of the recesses 22.

In order to unite all of these members, or 15 to hold the cap on the body and the ring upwardly beneath the flange of the body and in engagement with the stops 38 of the cap, a ferrule 39 is employed. The ferrule 39 is in the form of a ring or annulus of material 20 width, and having at its upper edge an in-turned flange 40 engaging snugly with the cap 36 at a point above the base flange 37 thereof, so as to engage a reduced portion of the cap to hold the latter from upward 25 movement through the flange 40 of the ferrule. Thus, the cap is held in the upper end of the ferrule 39. The lower end of the ferrule 39 is slipped downwardly over the body flange 21 and is forced over the ring 34, 30 with which it has a relatively tight engagement. The lower edge of the ferrule 39 is then spun over the rounded lower edge of the ring 34, or otherwise suitably interlocked with the ring, so that the ring 34 and the 35 ferrule 39 are adapted to turn as a unit.

It is a feature of this invention to provide a connection between the cap or ferrule, or other external rotatable part of the shaker, and the valve 31, so that upon the predetermined turning of the rotatable part, the 40 valve is swung from one position to a directly opposite position. To effect this result the structure of Figs. 1, 2, 3, and 6 may be employed, and wherein a link 41 is employed for connecting the valve 31 to the rotatable cap 36. This link 41 is in the form of a substantially U-shaped length of wire having the bridge or intermediate portion 42 thereof pivotally mounted in the intermediate tongue 30 of the valve 31, and extending 45 diametrically therethrough. This bridge portion 42 is introduced into the intermediate tongue 30 through a slot 43 extending from one edge of the tongue, as shown in 50 Fig. 2, to the intermediate portion thereof. This intermediate portion of the link provides a pivot for the link at the central portion of the valve 31. The link 41 has its opposite arms extending outwardly in substantial parallelism at the opposite sides of the valve 31 for a short distance, and then offset inwardly to provide opposed fingers or pins 44 and 45, which, by the inherent 55 spring action of the length of wire from which the link 41 is made, yieldingly bind

against the opposite sides of the valve 31. The finger or pin 45 terminates short of the peripheral edge of the valve, while the opposite finger 44 projects beyond the peripheral edge a distance equal substantially to the 70 thickness of the wall of the cap, to provide a combined anchoring and pivotal projection 46. The cap 36 has in one side, preferably immediately beneath the flange 40 of the ferrule, a bearing opening to receive the projection 46 of the finger 44. When the cap 36 is turned, the bearing 47 therein is moved in a circular path, and in a horizontal plane at right angles to the vertical axis of the body 20, and as the projection 46 of the finger 44 80 is held in the bearing, it effects the swinging of the link 41 about its pivot 42, and causes the fingers 44 and 45 to slide in registry over the opposite sides of the valve 31. As the link approaches the vertical plane of the partition 26, and as the fingers 44 and 45 slide over the sides of the valve, and as the finger 44 is held at all times at the same angle with respect to the horizontal plane through the base of the cap, the valve 31 is gradually 85 raised or swung up into a vertical position, as shown in dotted lines in Fig. 6, and upon the further rotation of the cap to carry the bearing 47 to the opposite side of the partition 26, the valve 31 is gradually swung 90 down and into the opposite position, which is shown in full lines in Fig. 6. It will be noted that during this change of position of the link 41 that the finger 45 is maintained 95 against the same side of the valve 31 at all 100 times, and therefore, when the valve is in the position shown in Fig. 1, or to the left, the finger 45 is on top, while when the valve is swung into its opposite position, or to the right, as shown in Fig. 6, the finger 45 is beneath the valve. The pivot 42 of the link is held centrally within the intermediate tongue 30 of the valve by the inner ends of the pins 32 and 33, which are of such length that they abut against the inner wall of the 110 cap 36 and engage at their inner ends against the opposite sides of the pivot 42. This structure admits of the easy assemblage of these parts, and admits of the formation of the parts of stock material, such 115 as sheet metal, and a single length of wire. It is thus seen, that, when the body 20 is held in one hand, and the ferrule 39 is grasped in the fingers of the opposite hand and given a turn in one direction, that the 120 ferrule turns, carries the connecting ring 34 therewith, and the latter, by reason of its interlocking engagement with the stops 38, turns the latter in the recesses 22, and rotates the cap 36, until the stops strike the 125 shoulders 23. This action takes place when the ferrule 39 is turned in either direction. The turning of the cap 36 swings the link 41 from one side of the partition 26, as 130 shown in Fig. 1, to the opposite side of the

partition, as shown in Fig. 6. The swinging of the link raises or scrapes the valve 31 against the inner spherical face of the cap 36, and removes accumulations from the inner face of the cap and deflects these accumulations back into the compartment 28, from which the same were deposited. When the valve 31 moves back from the position shown in Fig. 6 to the position shown in Fig. 1, the valve 31 scrapes the inner face of the cap in the opposite direction and removes the accumulations therefrom, and deflects the same back into the compartment 27, from which the accumulations were deposited. Thus, the valve not only alternately cuts off and opens the compartments 27 and 28, but it also deflects any deposits in the cap, which adhere thereto after the use of the device, and throws those deposits back into the compartment from which they came. It is, therefore, impossible for the contents of the compartments 27 and 28 to mix during the use of the device. When the valve is thrown over to the extreme positions shown in Figs. 1 and 6, the compartments 27 and 28, respectively, are in communication with all the perforations in the cap. It is, of course, understood that the ferrule 39 may be turned to any desired degree, so as to raise or lower the movable valve 31 into any desired angle to communicate the perforations 48 in the cap more or less with one or both of the compartments 27 and 28.

The present invention also provides an improved closure for the bottom of the body or receptacle 20. The closure, as shown in Figs. 1 to 5 inclusive, comprises a base 49, which may be of sheet metal as shown, and which tapers upwardly at a slight degree and is provided with a counter-sunk bottom 50, providing with the upper end of the base 49 a socket into which is tightly fitted and permanently secured, the lower end of the receptacle or body 20. This bottom 50 has a pair of diametrically opposed openings 51 and 52 in registry respectively with the compartments 27 and 28, so as to admit access to the compartments. An inward turned flange 53 is formed upon the lower edge of the base 49, and upon which the base rests. The flange 53 is relatively short, so as to provide a substantial opening 54 upwardly through the bottom of the base 49. Fitted within the base 49 is a closure disk 55 having a downwardly offset flange 56 adapted to seat upon the upper inner face of the flange 53 and to thus hold the disk 55 flat and tight against the lower side of the bottom 50. This disk 55 has a single opening 57 therethrough adapted, by the rotation of the disk 55 to register with the openings 51 and 52, one at a time, so as to admit access to the compartments 27 and 28, one at a time only, and thus prevent any

accidental mixing of the ingredients in filling the compartments. The disk 55 is provided with any suitable means for conveniently turning the same, and is shown in the present instance as being provided with a diametrically extending rod or pin 58, which has its ends secured through the opposite sides of the opposite flange 56. Thus, the pin 58 provides a finger hold for the reception of the fingers when inserted upwardly through the base 49, so that the disk 55 may be conveniently turned to register the opening 57 with either one of the openings 51 or 52 in the bottom of the desired compartment 27 or 28. The opposite compartment is held closed, so that in pouring a condiment in the open compartment, the accidental spilling of the condiment will prevent the same from falling into the closed compartment and mixing with the opposite condiment.

In Figs. 10, 11 and 12 of the drawings, there is disclosed a slightly modified form of connecting means between the rotatable cap 36 and the valve 31. The valve 31 is provided upon one side with an arcuate strap 59, which has inturned ends and reduced extremities providing stop shoulders 60 and clenching extremities 61. The extremities 61 are adapted for insertion through the valve 31, at spaced apart points, so as to position the strap 59, as shown in Fig. 10. In this position the body of the strap 59 is held away from the adjacent face of the valve 31, to provide a loop or confined slot beneath the strap. The extremities 61 of the strap are now turned over against the opposite side of the valve 31 to clench and positively secure the strap in place. The dome 36 has a base flange 37^a, which is preferably not interrupted, but is continuous in width throughout, and rests upon the upper face of a body flange 21^a of substantially the same width and being of uniform depth throughout. The cap 36 is united to the body 20 by the ferrule 39, which is of the same form, as shown in Fig. 1, and which has its flange 40 embracing the reduced portion of the cap 36, and its lower end turned in beneath the body flange 21^a. In this instance the ferrule 39 and its flange 40 are adapted to tightly bind against the cap 36 and its flange 37^a, so as to rotate therewith. It is readily seen from this structure, that when the ferrule 39 is turned upon the body 20 that it will rotate the cap 36 therewith. The cap 36 is further provided with a finger 44^a projecting inwardly through an opening 47^a formed in one side of the cap 36, the finger projecting into the loop beneath the strap 59 and being confined therein by the body of the strap and the adjacent side of the valve 31. This finger 44^a is carried upon one free end of a spring ring 62, which encircles the cap 36

immediately beneath the flange 40 of the ferrule, and is held in place upon the cap by the flange 40. It will be noted that the end of the ring 62 is crimped outwardly to provide a projection 63 from the outer end of which the finger 44^a is extended in a straight line and diametrically toward the geometrical center of the ring. The finger 44^a is preferably bent down slightly as

10 shown in Fig. 10, at its point of passage through the opening 47^a in the cap, so that the finger 44^a will extend at its inner end radially from the center of the valve 31.

15 The arcuate strap 59 is formed on a curve, the center of which is co-incident with the center of the valve 31. In each instance, it is desirable to have the valve 31 of substantially semi-circular form, so that the peripheral edge thereof will at all times fit 20 snugly against the inner spherical surface of the dome or cap 36. The turning of the cap and the ferrule thus carry the ring 62 therewith, and move the finger 44^a in a circular path, and in a constant horizontal 25 plane. This movement of the finger 44^a causes the latter to work and slide against the inner face of the strap 59, and swing the valve 31 in one direction. When the cap and ferrule are turned in the opposite 30 direction, the finger 44^a engages and slides against the adjacent surface of the valve 31 to swing the same in the opposite direction. The outer or upper end of the strap 59 forms a stop 38^a to engage the finger 44^a at 35 each of its turning movements, to thus limit the rotation thereof and determine to the user the extent to which the ferrule 39 must be turned to completely overthrow the valve in either direction.

40 In Figs. 13, 14 and 15, a second modified form of the valve operating means is shown, and wherein the valve 31 is engaged between a pair of inwardly extending fingers 44^b, carried upon the opposite free ends of a 45 spring ring 64 in the manner as disclosed in Figs. 10 and 11, in connection with the single finger therein, the fingers 44^b projecting through horizontally spaced apart openings 47^b formed in the side of the cap 36 immediately beneath the flange 40 of the ferrule 39. The turning of the ferrule 39 and the cap 36 moves the fingers 44^b therewith and engages the same alternately against the opposite sides of the valve 31 to swing 50 the same about the top of the partition 26, to produce the same result, as is effected by the above set forth constructions, shown in Figs. 1 and 10. The valve 31 is provided with a stud 65, at any suitable point near 55 the periphery thereof, and in the path of the fingers 44^b. The stud 65 is provided with relatively large heads at its opposite ends, which project beyond the opposite faces of the valve 31, so as to contact with 60 the inner ends of the fingers 44^b and limit

the turning of the cap 36 and the swinging of the valve 31. As shown in Fig. 15, one of the fingers 44^b is in contact with the adjacent headed end of the stud 65, so as to limit the turning of the fingers and the 70 swinging of the valve. The fingers 44^b are resilient, to allow a considerable throw of the valve when the cap and ferrule are turned.

In Figs. 16 and 17 there is shown a further modified form embodying the features of this invention, and wherein the body 20^c is provided in its opposite sides and near its upper edge with a pair of spaced apart detents 24^c to receive therebetween the upper 75 opposite edges of the fixed partition 26^c. Immediately above the detents 24^c, the body is provided with diametrically opposed openings providing bearings 66 to receive the opposite ends of a diametrically extending rock shaft 67, the ends of which project through the openings 66 and extend outwardly beyond the sides of the body 20^c. One end of the rock shaft 67 is provided with an upstanding segment 68, the opposite flat faces 69 of which constitute stops adapted to alternately engage against the upper face of an annular bead or flange 21^c surrounding the body 20^c adjacent its upper 80 end. The ring 34^c surrounds the upper end 90 of the body and has its inner thickness engaging beneath the flange 21^c and its opposite or outer thickness rising upwardly about the flange 21^c and against the opposite ends of the rock shaft 67. This ring 34^c snugly 95 receives thereover a ferrule 39^c, which, as shown to advantage in Fig. 17, is preferably integral with the base of the cap 36^c, and has its lower end spun over the lower rounded edge of the ring 34^c to securely 100 unite the ring to the ferrule, so that the cap, the ferrule, and the ring rotate as a unit. The ring 34^c has secured thereto, in its upper edge and at the opposite sides of the segment, the outer ends of a pair of flexible 105 connectors 71 and 72 which are crossed upon the peripheral surface of the segment 68 and are secured, as at 73 and 74 to the opposite ends or outer corners of the segment 68. Thus, when the ferrule 39^c is turned upon 110 the body 20^c, the cap 36^c is moved with the ferrule 39^c, and the ring 34^c is also moved therewith. The movement of the ring in one direction causes the connector 72, which may be in the form of a wire, a metal band, 115 or the like, to become taut and draw the segment 68 in the direction of travel of the ring 34^c, and thus rock the segment to raise the side 69 thereof from the flange 21^c and throw the segment over upon its opposite 120 side. This movement of the segment swings the valve 31^c over into its opposite position. The opposite turning of the ferrule 39^c causes the connector 71 to draw the segment 68 in an opposite direction, and thus rock 125 the segment 68 in an opposite direction, and thus rock 130

- the valve 31^c back to its original position. The valve 31^c is of semi-circular form, and has its inner edge seated in a longitudinal slot or recess 75 formed in the upper side of 5 the rock shaft 67. A spring 76 is arranged in the recess 75 longitudinally thereof, and engages against the inner edge of the valve 31^c to urge the same outwardly and upwardly at all times and thus tension the 10 valve against the inner surface of the cap 36^c. Thus, the valve 31^c at all times bears and scrapes against the inner face of the cap, so as to maintain the openings 48 in the cap clear at all times.
- 15 A still further modification of this shaker structure is shown in Figs. 18 and 19, wherein the body 20^d is integral with the cap 36^d, the latter being stationary upon the body. The cap 36^d, however, is of the semi-spherical form shown in Fig. 1, and has, at the 20 base thereof, an outstanding rib or flange 21^d formed annularly thereabout, and having therebeneath the inner thickness of a ring 34^d. The body 20^d has pressed inwardly therefrom the detents 24^d, providing spaced apart cleats between which the opposite edges of the partition 26^d are engaged for anchoring the partition in the body. The body 20^d is provided, immediately above the detents 24^d, with a cylindrical opening in each side, providing bearings 66^d to receive the opposite ends of the rocker shaft 67^d, which carries the valve 31^d. The ferrule 39 of Fig. 1 is employed, which 25 has its flange 40 engaging a reduced portion of the cap 36^d, and has its lower end spun or turned in around the lower curved end of the ring 34^d. Thus, the ferrule 39 and the ring 34^d are interlocked for rotation about the cap and the body as a unit. The same operating mechanism is used for 30 swinging the valve 31^d as is disclosed in Figs. 16 and 17, the distinction being that the cap 36^d does not rotate, but is integral with the body 20^d. The form shown in 35 Figs. 18 and 19 have been made the subject-matter of a separate application which was filed November 29th, 1916, Serial No. 134,155.
- 40 In all of the forms of the present invention, it will be noted that the body 20 is provided with a movable part, which is movable peripherally around the body, and may be grasped from any side thereof, so as to turn the movable part with respect to the 45 body to shift the valve and scrape the inner surface of the cap. The body or rotating part may be provided with suitable indicia to indicate the proper direction in which 50 to turn the ferrule, in order to so adjust the valve as to deliver either pepper or salt, or a predetermined admixture of both. In all 55 adjustments of the valve, it constitutes a partition co-extensive with the fixed partition 26 in the body to keep the ingredients

in the receptacle in their respective compartments and to deliver the same to the entire cap, or to the adjacent portion of the cap above the compartments.

It is, of course, understood that various 70 other modifications and changes may be made within the scope of the following claims, without departing from the spirit of this invention for the purpose of adapting the shaker to different designs for ornamental purposes, and to different kinds of materials and conditions found within the manufacture of the shaker according to this invention.

What is claimed is:—

1. A salt and pepper shaker comprising a body having a central partition therein to divide the body into separate salt and pepper receiving compartments, a valve mounted at the upper end of the partition 85 and movable to close communication with either of said compartments, a perforated cap carried upon the upper end of the body and communicating with said compartments, a ferrule surrounding the upper end of the 90 body and the base portion of the cap and retaining the latter in place on the body, and connecting means with the valve, whereby the turning of the ferrule actuates said valve to establish communication between the cap 95 and either of said compartments.

2. A salt and pepper shaker comprising a body portion having a compartment for salt therein and a second compartment for pepper, a valve in the top of the body to alternately open and close said compartments, a single cap on the upper end of the body communicating with both compartments, a 100 slideable member exterior of the body to be grasped by the fingers, said member retaining the cap on the body, and a connection between said valve and said slideable member for operating the valve upon the movement of the member to communicate a selected one of said compartments with said cap. 105

3. A salt and pepper shaker comprising a body portion having a compartment for salt and a second compartment for pepper therein, a valve in the top of the body adapted to alternately open and close the said compartments, a perforated cap on the upper end of the body communicating with both of said compartments, an annular operating member extending around the body adjacent to the cap and having a connection therewith to hold the cap to the body, means for limiting the right or left turning movement of said member, and a connection between said cap and said valve for operating the latter upon the movement of the operating member in either direction. 115

4. A salt and pepper shaker comprising a body having a central partition therein to divide the body into separate salt and pepper receiving compartments, a dome shaped 130

cap carried upon the upper end of the body and communicating with both of the compartments, a semi-circular valve hinged at the upper end of the partition and contacting at its peripheral edge with the inner face of said cap, a ferrule surrounding the upper end of the body and the cap, and a connection between the ferrule and the valve for swinging the valve about its pivot upon the turning of the ferrule, whereby to open the desired compartment to said cap to discharge the contents of the same through the cap and retain the contents of the opposite compartment from passing through the cap.

5. A salt and pepper shaker comprising a body having a partition therein to divide said body into separate compartments, a valve at the upper end of the partition and movable to close communication with either of said compartments, a perforated dome-shaped cap carried upon the upper end of the body and communicating with said compartments, an annular operating member extending around the body adjacent to the cap and adapted to be turned thereon, means for limiting the turning movement of said operating member, and means whereby the turning movement of said operating member imparts a shifting movement to the valve, said valve being semi-circular in form and having its peripheral edge conforming to and scraping against the inner surface of said cap in the movement of said valve, the valve in its extreme movement being shifted beyond the perforated portion of the cap so as to cause said portion thereof to be put in communication with either of said compartments.

6. A salt and pepper shaker comprising a body having a central partition therein, a cap rising from the upper end of the body, a valve hingedly mounted at the top of the body in the plane of the upper edge of the partition, said valve having its peripheral edge conforming to the inner surface of said cap, a ferrule surrounding the upper end of the body, and means between the ferrule and the valve to operate the latter upon the turning of the ferrule.

7. A salt and pepper shaker comprising a body, a partition in the body dividing the same into two compartments adapted to receive salt and pepper, a valve mounted at the end of the partition and adapted to be turned to alternately open and close the compartments, a perforated cap on the end of the body to house the valve, and a ferrule surrounding the base of the cap and having operative connection with the valve to swing the same upon the turning of the ferrule for opening the desired compartment to the cap.

8. A salt and pepper shaker comprising a body having separate compartments therein adapted to receive salt and pepper, a per-

forated dome-shaped cap rotatably mounted on the upper end of the body, a valve hinged in the body and adapted to be swung in opposite directions to alternately open and close the said compartments, said valve conforming at its edge to the curvature of the inner wall of said cap and adapted to bear thereagainst, and operating means for turning the cap in one direction and simultaneously swinging the valve in a different direction so as to scrape the inner wall of the cap by the different movements imparted to the cap and valve, respectively.

9. A salt and pepper shaker comprising a body having separate compartments therein for the reception of salt and pepper, a perforated cap rotatably mounted on the upper end of the body communicating with both of the compartments, a valve carried by the body and adapted to be actuated to alternately open said compartments, a ferrule surrounding the base of the cap and having connection therewith to turn the latter upon the movement of the ferrule, and a connection between the valve and the cap whereby upon the rotation of the cap the valve is shifted.

10. A salt and pepper shaker comprising a body having separate compartments therein for the reception of salt and pepper, a perforated cap rotatably mounted on the upper end of the body communicating with both of the compartments, a valve carried by the body and adapted to be actuated to alternately open said compartments, and means located adjacent the cap for turning the same and actuating the valve.

11. In a salt and pepper shaker, a body having a partition therein providing independent salt and pepper receiving compartments, a base fitted about the lower end of the body and having a recessed bottom adapted to support the body and provided with an opening for each compartment, said base having an inturned flange at its lower edge spaced below said bottom, a closure disk fitting in the base between said bottom and said flange, said closure disk having a single opening therein adapted upon the turning of the disk to be brought into register with either one of said openings in the bottom of the base, and a diametrically extending pin carried by the disk within the base, said base being adapted to receive the fingers through the lower end thereof for engagement with said pin to turn the disk.

12. A salt and pepper shaker comprising a body, a central partition in the body to divide the same into two compartments, a valve of semi-circular form hinged at its straight edge along the upper edge of the partition, a cap fitting over the upper end of the body and having a concavity corresponding to the peripheral edge of said valve, a ferrule surrounding the upper end of the

body and the cap to connect the same together, and a connection between said cap and said valve for swinging the valve upon the rotation of said cap whereby to regulate 5 the outflow of the salt and pepper through the cap by the turning of the same.

13. A salt and pepper shaker comprising a body having an outturned flange upon its upper end and stop shoulders in the edge of 10 the flange, a cap carried upon the upper end of the body and having an outstanding flange adapted to seat on the body flange and provided with opposed stops adapted for contact with said stop shoulders upon the rotation of the cap through a predetermined fraction of a turn, a ferrule surrounding the cap and the upper end of the body, a connecting ring arranged beneath the body flange and fitting into said ferrule whereby 15 20 25 30 35 40 45 50 55 60 65 70 75 80 85
